FAN CONSTRUCTION

Theodor Troller, Akron, Ohio

Application March 23, 1934, Serial No. 717,000

1 Claim. (Cl. 230—120)

This invention relates broadly to fan construction, and more particularly to fans designed for delivering fluid under pressure, and especially rotary fans for this purpose. The invention has 5 to do primarily with increasing the efficiency of such fans.

Rotary fans for delivering fluid under pressure, such, for example, as ventilating fans for mines, buildings, etc., are designed to deliver fluid 10 in a desired direction, but, due to various factors which cannot be avoided, certain of which arise by reason of the rotational movement of the fan, a tendency is created to impart to the fluid a movement having a component transverse of the 15 desired direction of delivery. This causes cross currents in the delivered fluid and reduces the efficiency of the fan.

For example, in a ventilating fan such as might be used for withdrawing air from a mine and 20 which has a rotor or propeller for moving or delivering the air being withdrawn in a stream moving substantially in a straight line, as within a conduit having a substantially straight axis substantially coaxial with the propeller or rotor, the 25 propeller blades have working faces designed to move the air in the delivery direction, but due to the shape of such blades, the rotational movement thereof and the friction between the air and blades the air is not actually delivered in 30 a solid homogeneous unidirectional stream. The shape of the moving blades and the friction between the air and blades cause the air in addition to moving in the delivery direction to move also in a direction generally transversely of the 35 delivery direction generally tangentially of the rotor. In other words, although the air has a major component of movement in the delivery direction, it has a minor component, but nevertheless a component of sufficient magnitude to 40 materially reduce the efficiency of the fan, in a direction perpendicular to the desired delivery direction and, consequently, in the usual construction perpendicular to the axis of the rotor.

The movement of the air transversely of the 45 delivery direction not only sets up cross currents, but also, due to the fact that the air has mass, results in centrifugal movement thereof. This, in turn, results in a condition in which the pressure builds up toward the periphery of the air 50 stream and drops toward its center. The axial velocity of the air is likewise greatest adjacent the periphery of the stream and decreases toward the center of the stream. The tangential velocity of the air, however, is greater near the 55 center of the stream than at the periphery.

There results a condition in which the air near the center of the stream downstream from the propeller may remain substantially stationary. As a matter of fact, it is not unusual for this air to move backwards or opposite the desired 5 direction of delivery. The low efficiency of the fan under these conditions will readily be appreciated.

I provide for eliminating the undesirable conditions above referred to and greatly increasing 10 the efficiency of fans for delivering fluid under pressure. I provide for counteracting the tendency of the rotor to cause the fluid to have a component of movement transverse of the desired delivery direction. This is preferably done 15 by means cooperating with the rotor to control the fluid flow. I prefer to use substantially stationary means and, in a fan of the type referred to above by way of example, to dispose the same 20 substantially in axial alignment with the propeller. The invention in its broader aspects is not limited to any particular type of fan, but for purposes of illustration will be described as embodied in a fan for moving fluid forward in a 25 conduit in a substantially straight line.

The desired results may be accomplished by using a series of circumferentially arranged 30 vanes which deflect the fluid, preferably either just before or just after it passes the rotor. The vanes are preferably designed to impart to the 35 fluid a movement roughly equal to its transverse component and opposite in direction so that the fluid is delivered generally along the conduit with a minimum of cross currents. Elimination of the radial component of movement of a fluid delivered by a fan of the type specifically referred 40 to above is particularly important and is effectively accomplished by my construction. The fluid is delivered with substantially uniform velocity throughout the cross section of the stream.

Other details, objects and advantages of the 45 invention will become apparent as the following description of certain present preferred embodiments thereof proceeds.

In the accompanying drawings I have shown 50 certain present preferred embodiments of the invention, in which

Figure 1 is a longitudinal vertical central cross-sectional view through a fan construction;

Figure 2 is an elevational view looking from 55 left to right in Figure 1;

Figure 3 is an elevational view looking from right to left in Figure 1;

Figure 4 is a fragmentary diagrammatic eleva- 55

tional view showing the shape of the conduit or outer fairing;

Figure 5 is a side view of one of the vanes;

Figure 6 is an end view of the vane shown in

5 Figure 5;

Figure 7 is a view of the vane looking downwardly in Figures 5 and 6, Figure 7 being to enlarged scale;

10 Figure 8 is a view similar to Figure 1, but relatively diagrammatic and to reduced scale, showing a modified construction;

Figure 9 is a cross section through a vane of the type having appreciable thickness; and

15 Figure 10 is a diagrammatic fragmentary view 15 showing how the angle α_m is measured.

Referring more particularly to Figure 1, reference numeral 2 designates a mine shaft or entry 20 extending generally horizontally and opening at the right-hand side of the figure. To assist in ventilating the mine it is desired to withdraw the spent air outwardly through the shaft 2. At the mouth of the shaft there is provided a conduit or outer fairing, designated generally by reference numeral 3, which has a substantially 25 square or rectangular inner extremity 4 closely fitting the shaft and a substantially square or rectangular outer extremity 5 terminating in a flared discharge portion 6. Intermediate the ends of the outer fairing or conduit 3 is a section 7 of circular cross section, which section is connected with the extremities of the conduit by sections 8 and 9, respectively, which are smooth transformation sections whose cross section changes gradually from a circle to a square or 30 rectangle. The transformation is illustrated by the diagrammatic showing of Figure 4.

There is provided a base 10 having uprights 11 extending within the conduit, which uprights support bearings 12 in which is journaled for 40 rotation a driving shaft 13 extending longitudinally of the mine shaft and disposed at or near its transverse center. Connected with the shaft 13 at its left-hand extremity, and in radial alignment with the section 7 of the outer fairing, is 45 a rotor comprising two propellers 14 each having two blades 15 extending in radially opposite directions, such propellers being mounted hub to hub with their blades extending substantially at right angles to one another, as shown in Figure 50 1, so as, in effect, to rotate as a single 4-bladed propeller. The propeller blades are so designed that when the propeller rotates in the counterclockwise direction, viewing Figure 2, or the clockwise direction, viewing Figure 3 (such directions being indicated by arrows), it withdraws air 55 from the mine shaft 2 and delivers it in a generally outward direction, or toward the right viewing Figure 1.

60 Keyed to the shaft 13 intermediate the bearings 12 is a pulley 16 through which the shaft 13 is driven by a belt 17 which extends out of the conduit and within tubular guards 18 therein, such guards being of generally streamlined 65 cross section, as shown in Figure 1, so as to reduce the resistance offered thereby to the air being delivered by the fan. The belt 17 is driven by any suitable source of power, as by an electric motor positioned in a room or building adjacent 70 the shaft.

70 There is provided an inner fairing designated generally by reference numeral 19 and which comprises a central generally cylindrical portion 20 substantially surrounding and enclosing the 75 bearings, shaft and pulley and supported by the

uprights 11, a substantially conical portion 21 extending upstream and a substantially conical portion 22 extending downstream. The portions 21 and 22 are to promote gradual lateral deflection of the air at the center of the shaft so as to avoid undue resistance to the air by the portion 20.

There are provided three vanes 23 equally spaced circumferentially and which are positioned immediately upstream from the rotor comprising the two propellers. The purpose of the vanes is to cooperate with the rotor to control the air flow so that the air will be delivered generally longitudinally of the conduit with a minimum of cross currents. As above stated, the 10 rotational movement of the rotor tends to impart to the air a movement having a component transverse of the desired delivery direction, and I design the vanes so as to counteract to at least a substantial extent this tendency of the rotor. 15 The vanes deflect the air in such manner as to impart thereto a movement roughly equal to the transverse component of the movement imparted by the rotor and opposite in direction.

20 Design of the vanes to accomplish the results 25 above referred to is a nice problem, as these vanes should give the desired effect but should not cause any appreciable reduction of the efficiency of the whole fan system by losses through friction on the vanes or by eddies and turbulence in 30 the moving fluid caused by the vanes. I have solved such problem partly by theoretical considerations and partly by experiment, correlating the results to produce a fan construction 35 approaching very closely a theoretically perfect fan. I shall now proceed to describe how the vanes are designed.

Both the blades and the vanes are preferably 40 equally spaced circumferentially to avoid unbalance. The number of vanes is preferably unequal to the number of blades of the rotor so as 45 to avoid impulses in the air stream which would be brought about when the respective blades would pass the respective vanes. In the preferred embodiment of the invention shown in 50 Figures 1 to 7, inclusive, I have shown the propellers as being of standard design having a greater pitch nearer the axis of rotation than near the outer ends of the propellers and three 55 vanes made of sheet metal. The upstream edge 50 of each vane extends substantially perpendicular to the axis of the rotor. Each vane then extends generally downstream toward the rotor and has a shape, dependent upon the rotor design, 60 which may be defined by the following formulae:

$$(1) L = \frac{1}{2} t_m \frac{1}{\tan \alpha_m} \frac{x_p}{x},$$

$$(2) r \tan p_r = \text{Const.}$$

$$(3) b_r = \frac{1}{2} L \tan p_r,$$

in which

L is the length of each vane in a direction parallel to the axis of the propeller;

t_m is the average width of each propeller blade;

α_m is the angle between the thickness center line of a section of each propeller blade in a plane perpendicular to the length of the blade at the center, in the direction of the length of the blade, 70 of its effective portion and the plane of rotation of any point on the blade;

x_p is the number of propeller blades;

x_v is the number of vanes;

p_r is the angle between a tangent at the edge 75

- of each vane nearer the propeller to the thickness center line of a section of the vane which lies in a first plane perpendicular to a second plane containing the axis of the propeller and the edge of the vane remote from the propeller, which edge extends substantially perpendicular to the axis of the propeller, which first plane is at a radial distance r from the axis of the propeller, and a line through the point of tangency 5 parallel to the axis of the propeller; and
 10 b_r is the width of each vane at a radial distance r from the axis of the propeller in a plane perpendicular to the axis of the propeller in a direction perpendicular to the edge of the vane 15 remote from the propeller.

The various terms used in the formulae are indicated in the more or less diagrammatic showings of Figures 5, 6, 7 and 10. It is believed that with the above explanations as to the various 20 terms and the showings of the drawings application of the formulae will be self-evident.

In order to obtain the first value of the angle p_r the known formula

$$25 \quad \tan p_r = \frac{u'}{v}$$

in which u' is the peripheral velocity of the air induced by the fan and v is the axial velocity of the air through the fan, both at a radial distance 30 r from the axis of the rotor, may be used. The values of u' and v may be obtained by experiment and measurement or they may be obtained mathematically, as well known in the art. When 35 one value of the angle p_r has thus been obtained, this being the value corresponding to a given radial distance r , the constant in formula (2) above may be calculated, and formula (2) may thereafter be used in calculating values of the angle p_r corresponding to other radial distances r .

- 40 The formulae which I have evolved define the shape of the vane so far as its length and breadth are concerned and give the direction in which the vane extends from any point along the edge thereof nearer the rotor. This is given for simplicity by the direction of the tangent at the vane edge nearer the propeller to the thickness center line of each vane section under consideration as the tangent has the same direction at the point of tangency as has the center line. 45 Although the center line is somewhat curved, it closely approximates a straight line at the edge of the vane nearer the propeller so that the tangent for some distance from the vane edge very closely approximates the section center line, 50 and in the practical working out of the shape of the vane the tangent itself may be used in place of the center line. Any error which might thus be introduced would be far less than the allowable deviation, as will be pointed out below. 55 As the opposite edge of the vane is a straight line perpendicular to the axis of the rotor, the shape of the vane is determined, as illustrated in Figure 7, by smoothly curving the respective section center lines so that they will assume superposed 60 relation at their left-hand extremities. This is usual practice in aerodynamic design, and each of the section center lines may independently curve to the ultimate line C (see Figures 5 and 7) or the lines may assume superposed relation in 65 groups before the line C is reached. In Figure 7 the two extreme lines are shown as assuming superposed relation at A and the three intermediate lines at B, the two composite lines thus produced becoming superposed at the ultimate 70 line C.

A few examples showing how my invention may be applied may be helpful in understanding it. As a first example let it be assumed that it is desired to deliver 150,000 cubic feet of air per minute against a pressure of 4" of water using 5 a rotor having a diameter of 96" turning at a speed of 1200 revolutions per minute. Good engineering practice would dictate that t_m should be about 10", 5 vanes would probably be used as against 4 propeller blades and the angle a_m 10 would be about 11°. Using these figures, $\tan a_m$ (11°) = .195 and

$$L = \frac{1}{2} \cdot 10 \cdot \frac{1}{.195} \cdot \frac{4}{5} = \text{approximately } 20"$$

The first value of the angle p_r would be calculated as above explained, and formulae (2) and (3) could then be used for obtaining the other values of the angle p_r and the values of b_r . The following table shows these:

r	p_r	$\tan p_r$	b_r
47.5"	14.75°	.263	2.65"
31.5"	21.5	.394	4.00"
14.5"	40.5	.855	8.5"

15

20

25

As a second example let it be assumed that it is desired to deliver 16,500 cubic feet of air per minute against a pressure of 5" of water, using 30 a rotor 24" in diameter turning at a speed of 3500 revolutions per minute. Under these circumstances a proper value for t_m would be about 3.5", 4 propeller blades might be used as against 3 vanes, and the angle a_m should be about 16°. 35 Tan a_m would then equal .287 and

$$L = \frac{1}{2} \cdot 3.5 \cdot \frac{1}{.287} \cdot \frac{4}{3} = 8.2"$$

If, however, considering a problem actually encountered in design, it should be desired to use the vanes as a support for the inner fairing (see Figure 8) the vanes would be made somewhat heavier and longer than theoretically necessary and I would take the value of L as being 10'. 40 The values of r , p_r , $\tan p_r$ and b_r would be as follows:

r	p_r	$\tan p_r$	b_r
11.9"	40.0°	.84	4.2"
9"	48.0°	1.11	5.5"
6"	59.0°	1.66	8.5"

45

50

If as a third example it should be desired to 55 deliver 1250 cubic feet of air per minute against a pressure of 2" of water with a propeller 5.8" in diameter turning at a speed of 5000 revolutions per minute, t_m should be approximately 2.2", the number of blades might be 4 as against 5 vanes, and the angle a_m should be approximately 28°. Tan a_m would equal .532 and

$$L = \frac{1}{2} \cdot 2.2 \cdot \frac{1}{.532} \cdot \frac{4}{5} = 1.65"$$

The values of r , p_r , $\tan p_r$ and b_r would be as 65 follows:

r	p_r	$\tan p_r$	b_r
2.8"	28.0°	.533	.44"
2.4"	32.0°	.626	.52"

70

It is not contemplated that the shape of the vanes as actually manufactured will in all cases 75

be exactly in accordance with my formulae, although I believe the formulae to define vanes of the most nearly perfect shape for accomplishing the desired results. For instance, in the second 5 example given above I arbitrarily increased the length of the vanes from 8.2" to 10" in order to increase the size and strength of the vanes sufficiently to adequately support the inner fairing. I find that satisfactory results are obtainable if the value of L is held within about 25 per 10 cent., more or less, of the theoretical value obtainable by application of formula (1), the value of the angle p_r is held within about 15 per cent., more or less, of the theoretical value obtainable 15 by application of formula (2), and the value of b_r is held within about 10 per cent., more or less, of the theoretical value obtainable by application of formula (3). These are usual engineering variations.

20 In Figure 8 there is shown a modified form of construction in which the vanes are positioned downstream with respect to the rotor, the vanes being used to support the portion of the inner fairing disposed downstream from the rotor. 25 The portion of the inner fairing upstream from the rotor would have to be supported otherwise in any appropriate way. In the construction diagrammatically illustrated in Figure 8 an electric motor 24 is mounted within the inner 30 fairing, the rotor 25 being driven directly from the motor shaft 26. The wires for the motor could be led in in any appropriate manner, as through the nose of the inner fairing. The inner fairing in Figure 8 is substantially a conventional airship hull, as contradistinguished 35 from the inner fairing of Figure 1, this being a matter of design and convenience. Such an airship hull offers less resistance to the airflow, but a construction such as shown in Figure 1 is 40 cheaper to manufacture.

45 The vanes need not be of sheet metal as shown in Figures 1 and 8, but may be of appreciable thickness and may be constructed, for example, out of wood or metal forms covered with sheet metal, canvas, etc. When vanes of appreciable thickness are used they should have airfoil sections, as shown at 23' in Figure 9, in which the nose or upstream extremity of the section is toward the right. My formulae contemplate the use 50 of vanes of appreciable thickness, the angle p_r , as above indicated, defining by the direction of its tangent at the vane edge nearer the propeller the direction of each vane section center line. When vanes of appreciable thickness are used their 55 surface contours as air foil sections are easily de-

terminable by methods well known in the art. When sheet metal vanes are used this is unnecessary due to the fact that for aerodynamic purposes the thickness of the sheet metal is negligible and its surface may be substantially conformed to the center lines as determined by my formulae. 5

While I have shown and described certain present preferred embodiments of the invention, it is to be distinctly understood that the same is not limited thereto but may be otherwise variously 10 embodies within the scope of the following claim.

I claim:

In combination, a rotary propeller for moving fluid in a direction generally axially of the propeller and means cooperating with said propeller to control the fluid flow, said means being mounted substantially in axial alignment with the propeller and comprising a series of circumferentially arranged vanes, said propeller and vanes being 20 designed, with usual engineering variations, in accordance with the following formulae:

$$(1) \quad L = \frac{1}{2} t_m \frac{1}{a_m} \frac{z_p}{z_r}$$

$$(2) \quad r \tan p_r = \text{Const.}$$

$$(3) \quad b_r = \frac{1}{2} L \tan p_r,$$

in which L is the length of each vane in a direction parallel to the axis of the propeller; t_m is the average width of each propeller blade; a_m is the angle between the thickness center line of a section of each propeller blade in a plane perpendicular to the length of the blade at the center, in the direction of the length of the blade, of its effective portion and the plane of rotation of any point on the blade; z_p is the number of propeller blades; z_r is the number of vanes; p_r is the angle between a tangent at the edge of each vane nearer the propeller to the thickness center line of a section of the vane which lies in a first plane perpendicular to a second plane containing the axis of the propeller and the edge of the vane remote from the propeller, which edge extends substantially perpendicular to the axis of the propeller, which first plane is at a radial distance r from the axis of the propeller, and a line through the point of tangency parallel to the axis of the propeller; and b_r is the width of each vane at a radial distance r from the axis of the propeller in a plane perpendicular to the axis of the propeller in a direction perpendicular to the edge of the vane remote from the propeller. 30 35 40 45 50 55

THEODOR TROLLER. 55
